(57) **CLAIM**

The ornamental design for a fecal occult blood detector, as shown and described.

DESCRIPTION

FIG. 1 is a perspective view of a fecal occult blood detector, showing our new design;

FIG. 2 is a top view thereof;

FIG. 3 is a bottom view thereof;

FIG. 4 is a side view thereof;

FIG. 5 is an opposite side view thereof;

FIG. 6 is a rear view thereof;

FIG. 7 is a front view thereof; and,

FIG. 8 is a sectional view along Lines 8-8 of FIG. 2.

The broken lines immediately adjacent the shaded areas represent the bounds of the claim, while all other broken lines are directed to environment and are for illustrative purposes only. The broken lines form no part of the claimed design.
